GAS FILLED TUBE

Hans J. Spanner, Berlin-Wilmersdorf, Germany,
assignor to Electrons, Inc., a corporation of
Delaware

Application February 20, 1930, Serial No. 429,889
In Germany March 4, 1929

3 Claims. (Cl. 250—27.5)

This invention relates to gas filled tubes having means for controlling either the time at which ionization begins within the tube, or the rate at which ionization proceeds. Due to their operation, and arrangement of parts hereinafter described, tubes constructed in accordance with my invention are particularly adapted to control relatively large quantities of power.

The invention provides a structure in which 10 the control means employed is preferably without the tube and results in a device which may be easily manufactured, and which is relatively inexpensive. The positioning of the control electrode outside the tube also screens the electrode 15 from particles sputtered off by the cathode.

The invention also affords a means for variably controlling the time, after each positive half cycle begins, at which the tube will rectify alternating current, thereby varying its average direct current output. The arrangement disclosed 20 also results in an efficient relay for use with direct currents.

The features and operation of the invention will be apparent from the following description and the accompanying drawing, in which

25 Fig. 1 illustrates a preferred construction in accordance with my invention;

Fig. 2 shows the invention as applied to another form of tube;

30 Fig. 3 shows the distribution of potential drop obtained, both before and after ionization starts; and

35 Fig. 4 illustrates graphically how the invention may be used to control the average value of the direct current output in an alternating current rectifier.

In my invention the amount of negative space charge which is neutralized by the positive ions of the gas within the tube may be controlled and 40 thereby the strength of the current flow varied so as to permit the tube to function as a control means for relatively large currents, which currents may be either alternating or direct in character.

45 Referring to Fig. 1, a gas filled tube 1 is shown connected in such manner as to rectify alternating current. An anode 2 and a cathode 3 in the form of a filament are sealed within the tube. A metallic shield 4 is provided for controlling the point at which ionization of the tube begins. This shield or control member 4 is in the form of a cylinder which closely fits the exterior of the tube and extends over the distance 50 between the electrodes, although it will be obvi-

ous from the following description that various other forms may be used.

If a source of alternating current is supplied to the input of the tube, the latter serves as a rectifier to deliver direct current to its output terminals. The filament 3 may be energized from the secondary 5 of a transformer, the primary 6 of which may be connected either to the input or other desired source of alternating current. A connection 7 is made to the electrical center of the filament circuit and serves to connect one side of the input circuit and also the control circuit to the filament circuit. The source 8 of control voltage may be obtained from a battery, as shown, or it may be obtained from 10 an alternating current source. The other side of the control circuit is connected thru a potential controlling device 9 to the control electrode 4. The plate 2 is connected to one of the direct current output terminals, the other output 15 terminal being connected to the alternating current source as shown. The scheme of connections is illustrative only, and may be widely varied for different purposes by those skilled in the art.

20 In the foregoing arrangement the potential of member 4 will control the point at which ionization starts on each positive half cycle of the alternating current to give the effect shown in Fig. 4, which result is obtained by neutralizing 25 the positive field of the plate in the neighborhood of the filament. The resultant electrostatic field about the filament is thereby reduced and the electrons emitted by the filament do not acquire sufficient velocity to ionize the gas and start the 30 discharge until the input voltage reaches the desired value. Once ionization starts, however, the resistance of the gas path between the filament and plate becomes relatively low, and practically all of the potential drop across the tube 35 is concentrated near the filament as shown by Fig. 3.

35 The potential of the control member will in general be made more negative than that of the filament. The degree depends upon the time at 40 which the ionization is to start—the more negative the control member is made with respect to the filament, the later ionization will start, and vice versa.

45 While the source of control potential in Fig. 1 is shown for convenience as supplied by a battery, this potential may be obtained from any other suitable source of supply, and any suitable means for controlling its potential may be used.

50 Due to the fact that the exterior shield or 55

- control element is separated from the tube electrodes by the insulating wall of the tube, various of the disadvantages of the conventional grid element within a tube are obviated. With an inside grid, even though it may have the same potential as the filament, the grid in service often becomes an emitting element itself due to condensation on its surface of the emissive coating material of the filament which is thrown off.
- 10 An inside grid may also acquire sufficient heat from the filament to cause it to become emissive, and any emission on the part of the control element will cause ionization to take place. The instant that any ionization occurs the cut-off or control function of the tube is seriously impaired.
- 15 An important advantage of an exterior control member lies in the fact that it can be completely insulated from the power circuit which it controls, if so desired. The use of an exterior control member also provides a simplicity of construction and reduces the difficulty of making a seal.

20 An inside grid also occludes a considerable quantity of gas, and as it is an expensive undertaking to drive out all of the occluded gas in a large quantity of metal, my construction overcomes this disadvantage.

25 Fig. 2 illustrates another form of my tube having different shaped electrodes, and connected to control a direct current circuit, but each of the tubes may be used with either direct or alternating currents. As connected in Fig. 2, when a direct current voltage is applied to the tube the gas is continuously ionized, and in such case the current flow can be varied dependent upon the number of ions in the discharge path. This 30 ionization can be controlled by choosing the proper gas density and varying the potential of the control member. Thus, when the shield is very negative with respect to the filament, it attracts a large number of ions from the discharge path and thereby permits the building up of a space charge which decreases the direct current output. As the shield is made less negative the 35 ions are released to neutralize the space charge and thereby increase the direct current output. It is particularly advantageous to have a large surface for the control electrode when using the same with direct current to neutralize a large quantity of ions, and my arrangement presents 40 this advantage.

45 When used with direct current circuits, the gas pressure is an important factor to give the critical relay action desired. The pressure should be so chosen that with no potential on the control member there will be approximately enough ions present in the discharge stream to just neutralize the space charge to prevent an appreciable space 50 charge drop. The proper gas pressure will depend upon various factors, such as the current flow, the size of the electrodes, and the configuration of the tube. There are various methods known to those in the art by which the proper density for a given gas may be determined. A

5 very simple method is to decrease the gas density until the voltage drop across the tube begins to rise above the ionizing voltage and at this point the gas pressure will be sufficient for all practical purposes. The pressure may, however, vary within certain limits, and generally can be somewhat higher because it will be decreased in every instance by occlusions. It may be desirable to deliver additional ions in certain quantities from either an auxiliary electrode within the tube, by 10 varying the pressure of the gas within the portion of the tube adjacent the electrodes, or by introducing the desired ions from external sources.

15 It will be appreciated from the foregoing by those skilled in the art that my tube may be utilized as a valve to efficiently rectify or control relatively large quantities of power, and may be used to replace circuit breakers, motor starters, rheostats, and various other control apparatus. The tube may also be used as an oscillator since 20 it has all of the elements necessary to control the oscillation of a tube in the well-known manner.

25 Many other and varied uses will be obvious to those skilled in the art without departing from the spirit of my invention, and I do not wish to be limited except as indicated by the scope of the appended claims.

I claim:

30 1. In a discharge tube, an anode, a heatable electron emissive cathode and a gaseous medium, the cathode being subjected to disintegration of electropositive substances, a control electrode of large surface surrounding the total length of the discharge path outside of the wall of the tube and adapted to control the amount of positive 35 ionization in the discharge field, the said gaseous medium having a pressure which, with no potential on the control electrode, gives a voltage drop from anode to cathode slightly higher than the ionization potential of said medium.

40 2. In a discharge tube, an anode, a heatable emissive cathode, an ionizable medium at a pressure which gives an operating voltage drop across the tube above the ionizing voltage, the cathode being subjected to disintegration of electropositive substances, and a control electrode of large 45 surface extending along substantially the total length of the discharge path and protected at its surface from said disintegrated substances, said control electrode cooperating with said medium to control the space current flow.

50 3. In a discharge tube, an anode, a fixed thermionic cathode and a gaseous medium, the cathode being subjected to disintegration of electropositive substances and the density of said medium being such that the voltage drop across the tube is slightly above the ionizing voltage, and a control electrode substantially surrounding the discharge path and protected at its surface from disintegrated cathode material, said control electrode being adapted to attract positive 55 ions thereto and thereby control the amount of positive ionization in the discharge field.
